UNITED STATES PATENT OFFICE.

EMIL HOFFMANN, OF COLOGNE, GERMANY.

TENSIONING AND LOCKING DEVICE FOR WIRE-BINDING MECHANISMS.

Application filed June 29, 1926, Serial No. 119,412, and in Germany July 1, 1925.

The object of the present invention is a tensioning and locking device for wire-binding mechanisms, in which auxiliary holding members are provided which move together with the actual tensioning members, and hold the short cut ends of the wire, which are pushed past each other while tensioning is being effected, during the twisting operation. This device has in comparison with the known tensioning and locking devices for wire-binding mechanisms, in which the ends of the wires are drawn past each other, the advantage that the cutting to waste or loss, which takes place on cutting away the remaining ends of wire, is obviated. The auxiliary holding members, which are located on opposite sides of the small pinion serving to twist the ends of wire, and between the two tensioning members, are connected by means of push rods each to the opposite tensioning member, so that they move simultaneously with the ends of the wire.

The drawings show in a constructional form the new tensioning and locking device. Fig. 1 illustrates the same in use, as seen looking downwards after the wire wound round a box or like article has been firmly tensioned, and just before the twisting of the wire ends which are lying one beside the other.

Fig. 2 is a view of the same device after the wire ends have been twisted together, but as seen in front elevation; Fig. 3 is a cross-section through the tensioning and locking device along the line 3—3 of Fig. 1. Fig. 4 shows the device for twisting the ends of the wire in side elevation.

Fig. 5 shows the auxiliary holding members in side elevation.

The tensioning and locking device consists in a known manner of a threaded spindle *c* having on one half a right hand thread and on the other a left hand thread, and 45 rotatably mounted in two stationary brackets *b* upon a base plate *a*. The spindle *c* can be rotated in either direction by means of a lever *d* which by means of an adjustable pawl *f* engages with a pinion *g* fast 50 upon the threaded spindle *c*. Two internally-threaded members *h* are also mounted upon the spindle *c*, and are provided in front with a device for holding the ends of the wire. Between the two tensioning members *h* is located a device for twisting the ends of the wire, which as shown in Fig. 4 consists of several pinions which interengage and are located between the two cheeks *i*. The final driven pinion *k* has a slot *l* in which the two ends of the wire lie close to one another, being free however. The device for twisting the ends of wire *m* is actuated by means of a cranked handle *n*, after the wire has been firmly tensioned by moving the two tensioning members *h*. 60 Whilst with the known tensioning and locking devices for twisting wire the two ends of wire are drawn together past each other, and the ends used to fix the wires in the tensioning members have to be cut 65 away after the twisting has taken place, with the new tensioning and locking device the ends of wire are pushed together past each other. To effect this, auxiliary holding members *o*, which move simultaneously with the tensioning members *h*, are provided for holding the ends of wire *m* which are pushed together and past each other during the twisting operation. These auxiliary members are provided with a slot *r* in which the 70 ends of wire lie closely side by side but free and are held therein by means of a drop-catch *p*. The auxiliary members *o* are arranged on opposite sides of the small pinion *k* for twisting the ends of wire and between 75 the two tensioning members and are connected each with the opposite tensioning member *h* by means of rods *s*. Since the two rods *s* as well as the ends of wire *m* are pushed towards and past each other, the rod 80 of one auxiliary member *o* passes freely through the other auxiliary member *o* and the cheeks of the device for twisting the wire ends, and vice versa. 85

I claim:

1. In a tensioning and locking device for wire-binding mechanisms in which the wire is finally twisted for securing purposes, tensioning members for straining the wire and auxiliary holding members receiving motion from said tensioning members and adapted to hold the ends of the wire which are pushed towards and past each other during the twisting operation. 90

2. In a tensioning and locking device for wire-binding mechanisms in which the wire is finally twisted for securing purposes, tensioning members for straining the wire, auxiliary holding members for holding the ends of the wire during the twisting operation, 105

110

and push rods connecting each auxiliary holding member to the opposite tensioning member.

3. In a tensioning and locking device for wire-binding mechanisms in which the wire is finally twisted for securing purposes, tensioning members for straining the wire, auxiliary holding members for holding the ends of the wire during the twisting operation, and push rods connecting each auxiliary holding member to the opposite tensioning member and passing slidably through the other auxiliary holding member.

4. In a tensioning and locking device for wire-binding mechanisms in which the wire is finally twisted for securing purposes, tensioning members for straining the wire, auxiliary holding members for holding the ends of the wire during the twisting operation, drop-catches for securing said ends in said auxiliary holding members, and push-rods connecting each of said auxiliary members to the opposite tensioning auxiliary holding member.

EMIL HOFFMANN.
